UNITED STATES PATENT OFFICE

MILES DARWIN PERRY, OF PARKERS LANDING, PENNSYLVANIA

OIL-WELL PULLING MACHINE

Application filed September 21, 1928. Serial No. 307,535.

The present invention relates to a portable oil well pulling machine for pulling out and lowering oil well casings, tubings and rods.

At the present time, it is customary to do such work with a team, and a cable passed over a pulley suspended from a temporary derrick.

This method is found to be slow and hard to operate, and it is therefore one of the principal aims of the present invention to provide a machine for more readily and easily performing the above operations and in an efficient and reliable manner.

A further object of the invention is to provide an oil well pulling machine of the above mentioned character, which includes low and high speed winding drums, the high speed drum being detachably secured upon the low speed drum.

Still a further object is to provide an oil well pulling machine of the above mentioned character, temporarily holding the weight of the tubing or tool and taking the weight off of the team or source of power, in case of an emergency.

Still a further object is to provide an oil well pulling machine of the above mentioned character which is simple in construction, inexpensive, strong and durable, and further well adapted to the purpose for which it is designed.

Other objects of the invention will become apparent as the nature of the invention proceeds and when taken in connection with the accompanying drawings.

In the accompanying drawings:

Figure 1 is a side elevation of the oil well pulling machine embodying my invention.

Figure 2 is a front elevation of the machine, parts being shown in section.

Figure 3 is a sectional view, taken approximately upon the line 3-3 of Figure 1, looking downwardly.

Fig. 4 is a vertical sectional view, taken on the line 4-4 of Figure 2.

In the drawings, wherein for the purpose of illustration is shown the preferred embodiment of my invention, the numeral 1 designates the oil well pulling machine, the same comprising a base 2, on which is secured the vertically disposed rectangular shaped frame 3. A pair of vertically disposed standards 4 and 5 are secured at their lower ends on the base 2, while the upper ends are secured to the adjacent sides of the frame 3. 50 The cross bar 6 extends transversely across the lower end portions of the angularly disposed standards secured thereto.

A horizontally disposed cross beam 7 is arranged between the intermediate portions of the spaced standards 4 and 5, and the purpose of this cross beam will be presently described. Diagonally disposed braces 8 are provided for the frame 3, as more clearly illustrated in Figure 2 of the drawings. 65

A pair of bearings denoted by the reference character 9 is secured on the forward edge of the intermediate portions of the standards 4 and 5 and extending through these bearings and arranged in alignment with each other is 70 the shaft 10. One end of the shaft protrudes beyond the side of the frame 3 and terminates in a squared crank handle receiving portion 11, for a purpose to be presently described.

A relatively large windlass 12 is removably keyed to the shaft 10 for disposition inwardly of the side standard 5 and secured to the inner side of the windlass 12 is the brake drum 13, the latter being of a diameter slightly greater than that of the windlass as more 75 clearly disclosed in Figure 2. Securing bolts 14 extend through the outermost sides of the windlass and brake drum, connecting the parts together, and this is also clearly illustrated in Figure 2 of the drawings. 80

The outer side of the windlass 12 is formed with an annular series of spaced openings 15, as disclosed in Figure 1, for receiving the removable pin 16, for a purpose also to be presently apparent. 85

A power cable (not shown) is adapted to be attached at one end on the windlass 12 and is capable of being wound around and unwound from the windlass for transmitting power to the shaft 10, on which said windlass is keyed, and a suitable guide 17 is provided for this cable, the other end being adapted for attachment to the team of horses or other draft (not shown). This guide is of a substantially U-shaped structure, the ends of the arms thereof being secured to the cross beam 7, while the arm portions of the U-shaped guide are slightly curved and disposed above the windlass as clearly suggested in Figures 1 and 3 of the drawings.

A low speed drum 18 is keyed on the other end portion of the shaft 10, inwardly of the standard 4, and a circular plate 19 is secured against the outer end of this low speed drum 18. A sectional high speed drum 20 is detachably secured around the low speed drum 18 and the diameter of the high speed drum is slightly less than the outer diameter of the circular plate 19, and the outer edge portion of the plate 19 will cooperate with the outer face of the brake drum 13 in retaining the elevating or lowering cable 21 on said winding drums, regardless of which one of said winding drums is used.

The high speed drum 20 is preferably constructed so as to provide hingedly connected sections as shown at 20', and any appropriate means may be provided for connecting the free ends of the sections together in assembled relation about the low speed drum 18 and the cable 21 in winding position will retain these sections together, said hinged sections consisting of a split band which is braced on the drum 18 by means of members 18'.

Pins 22 extend radially from the outer face of the high speed drum 20, the ends are adapted to divide the drum 20 into two sections; one section being designed to receive the slack cable which is a preliminary process to the actual pulling action, or in other words when the weight of the casing or tubing begins to draw the cable taut the slack part of the cable is then transferred to the adjacent section and the actual pulling process or winding of the remainder of the cable then takes place on the bare section thus eliminating the danger of having the cable snap or crackle which very often happens when a taut cable is wound over a slack cable.

Elongated bolts 23 extend through the central portions of the windlass 12, brake drum 13, and the low speed winding drum 18, respectively, in spaced relation around the shaft 10, whereby the parts are secured together in abutting relation on the driven shaft in a detachable manner. The elevating and lowering cable 21 is connected at one end to the outer side portion of the brake drum 13, as at 23', and when the high speed winding

drum is positioned around the low speed drum 18, the cable 21 will be wound around the drum 19 between the radial pins 22 and the outer side of the brake drum 13, as suggested in Figure 2. The other end of the cable is trained over a suitable pulley (not shown) and is connected to the tubing or drill rod while being raised from the well.

The frame 3 is provided with anchor post receiving staples 24, whereby said structure will be rendered stationary during the use of the machine. The anchoring post is adapted to extend through the staples and is driven into the ground adjacent the well. For the purpose of controlling the speed and rate of descension of the rods and tubing, when lowering the same into the well, there is provided a particular weight mechanism that includes a brake band 25, that encircles the peripheral face of the brake drum 13, for frictional engagement therewith.

A lever 26 is formed at its rear end with a horizontally disposed eye 27, and forwardly of the horizontal eye 27, said lever is formed with a right angularly disposed eye 28 that is pivotally connected with the staple 29 that extends upwardly of the cross beam 7 in a manner as shown in Figures 2 and 3. A screw eye 31 is threaded into the rear side of the cross beam 7, for disposition below the horizontal eye 27, and bolt 30 that is operatively connected at its lower end to one end of the split brake band 25, is threaded and disposed through the aligned eyes 31 and 27 and a nut 32 is threaded on the upper end of the eye bolt 30 for engagement with the upper face of the horizontal eye 27 formed on the rear end of the lever 26. A coil spring 33 encircles the eye bolt 30, and is disposed between the guide eye 31, and the connection 34, the lower end of the eye bolt and one end of the brake band. The other end of the brake band is attached to the cross beam.

The forward end portion of the lever 26 provides a handle whereby when said handle portion is depressed, said bolt 30 is raised, causing the contraction of the brake band around the drum, in a manner readily obvious from the construction disclosed in Figure 1.

By placing the pin 16 in one of the openings 15, the rotation of the shaft and the drums arranged thereon is limited in one direction so as to maintain the tubings or rods in an elevated position. A ratchet wheel 35 is keyed on the outer end portion of the shaft 10, inwardly of the square portion 11, and adapted for cooperation with the ratchet wheel 35 is a pivoted pawl 36, carried by a lever 37 that has a pair of plate members 38 secured on opposite sides of the portion of the lever, and the rear ends of these plates are formed with eyes to accommodate the shaft 10, the eye portion of the plates being disposed on opposite sides of

the ratchet wheel 35, in the manner as more clearly shown in Figure 2. A pawl 36 is pivoted between the plates 38 and normally when the machine is in operation, the pawl is disengaged from the ratchet teeth of the ratchet wheel 35, and the lever 37 is swung downwardly with its free end resting on the ground.

When it is desired to hold the weight of the tool or the tubing for a moment, or for the purpose of taking the weight off of the team or source of power in emergency cases, the lever 37 may be raised and the pawl 36 brought into engagement with the ratchet wheel 35, as shown in Figure 1.

When using the machine for light work, instead of employing a team of horses to draw the windlass and the shaft on which the windlass is secured, a hand crank 39 may be slipped over the squared end 11 of the shaft 10 and the machine then operated by hand.

A hook 40 is secured on the side of the standard 5, for receiving the locking pin 16 when the latter is not in use.

It will thus be seen from the foregoing description that I have provided an oil well pulling machine for use in raising and lowering pipes, casings and rods, and the simplicity of my machine enables the same to be efficiently operated. Also, the operations in removing or lowering tools or tubing into the well is expedited with a machine of this character. The structure of the machine is such as to permit the parts to be readily and easily assembled or disassembled.

While I have shown the preferred embodiment of my invention, it is to be understood that various changes in the size, shape and arrangement of parts may be resorted to, without departing from the spirit of the invention or the scope of the appended claims.

I claim:

1. In an oil well pulling machine of the class described, a horizontally disposed driven shaft, a support therefor, actuating means for said shaft, a low speed winding drum secured on the shaft for rotation therewith, and a high speed drum detachably secured around the low speed drum for rotation with said shaft, said high speed winding drum including complementary sections, hinges connecting the sections, and means consisting of the cable on the drum sections for securing the sections against accidental swinging movement relative to one another on said hinges during the winding operation.

2. In a machine for pulling oil pipes and the like, a horizontally disposed driven shaft, a support therefor, a brake drum secured to the shaft intermediate the ends thereof, a pull cable receiving windlass secured on the shaft for rotation therewith and to actuate the same engaging one side of the brake

drum, a winding drum arranged on the shaft in engagement with the opposite side of the brake drum, bolts extending through the sides of the windlass, brake drum and winding drum respectively for securing the same together as a single unit, an elevating and lowering cable connected with the winding drum and pins extending radially from the outer face of said winding drum for the purpose specified.

In testimony whereof I affix my signature.

MILES DARWIN PERRY.
